Inventor:

Otis W. Stearns.

UNITED STATES PATENT OFFICE.

OTIS W. STEARNS, OF JOHNSON, VERMONT.

IMPROVEMENT IN WOODEN TUBING.

Specification forming part of Letters Patent No. **35,186**, dated May 6, 1862.

To all whom it may concern:

Be it known that I, OTIS W. STEARNS, of the town of Johnson, in the county of Lamoille and State of Vermont, have invented a new and Improved Tubing, of which the following is a specification.

The nature of my invention consists in constructing a tube of wood, which I make in two parts and match together. I then wind the tube firmly from end to end with metallic wire or any other substance. The joints or sections I fasten or connect together by screwing or driving them into metallic bands or ferrules, the whole to be covered with some durable paint or coating.

To enable others skilled in the art to make and use my invention, I will proceed to describe its construction, reference being had to the accompanying drawings.

In drawing No. 1, A A represent two sections of the tubing in working order. B represents the band or ferrule into which the

sections are screwed or driven. C represents the strainer, which is constructed in socket form. D D represent the matching where the parts are put together. E represents the water-passage. F F represent the metallic wire with which the aqueduct is wound or bound together.

Drawing No. 2 represents one section of the aqueduct laid open, so as to show the inner surface, and lettered to correspond with drawing No. 1.

What I claim as my invention, and desire to secure by Letters Patent, is—

The tube formed by the combination and arrangement of the parts A A, ferrule B, strainer C, matching pieces D D, channel E, and wire F F, or its equivalent, substantially as described.

OTIS W. STEARNS.
